UNITED STATES PATENT OFFICE.

HOWARD C. BROWN, OF NEW YORK, N. Y.

BRUSH.

1,117,778.

Specification of Letters Patent. Patented Nov. 17, 1914.

Application filed February 20, 1914. Serial No. 819,967.

To all whom it may concern:

Be it known that I, HOWARD C. BROWN, a citizen of the United States, and a resident of the city of New York, borough of Brooklyn, in the county of Kings and State of New York, have invented a new and Improved Brush, of which the following is a full, clear, and exact description.

This invention relates to brushing and scrubbing, and has particular reference to the construction of brush heads whereby such devices are rendered more convenient and serviceable than those commonly employed.

Among the objects of the invention is to construct a brush frame or head of sheet metal, principally by stamping from metal of uniform thickness, certain fastening devices being provided whereby the head may be easily taken apart and reassembled with a new set of bristles or brushes therein.

Another object of the invention is to construct a whitewash or bill poster's brush in such a manner as to render the removal of worn bristles an easy expedient.

The foregoing and other objects of the invention will hereinafter be more fully described and claimed and illustrated in the drawings forming a part of this specification in which like characters of reference indicate corresponding parts in all the views, and in which—

Figure 1 is a perspective view of a brush head made in accordance with a preferred embodiment of this invention, the location of the bristles being indicated in dotted lines; Fig. 2 is a partial plan and transverse section on the line 2—2 of Fig. 1 or just above the bristles; Figs. 3 and 4 are vertical transverse sections on the corresponding lines of Fig. 2; and Fig. 5 is a view of one of the bundles of bristles detached.

The several parts of the device may be made of any suitable materials, and the relative sizes and proportions, as well as the general design of the mechanism, may be varied to a considerable extent without departing from the spirit of the invention hereinafter more fully set forth and specifically claimed.

Referring to the drawings for a more specific description of the invention, I show at 10 a pair of face plates made preferably in duplicate, each plate being in the form of sheet metal stamped and swaged or other-

wise bent, as indicated, whereby there are formed a series of substantially semi-cylindrical sockets 11. The number of such sockets shown herein for each brush is seven, 60 but it will be understood that more or less of such features may be employed. Instead of forming the sockets semi-cylindrical, they may be slightly tapered or frusto-conical, as illustrated. Between each two adjacent 65 sockets 11 is a connecting web 12 shown in the form of a trapezoid or having its upper and lower edges parallel and its side edges divergent corresponding to the taper of the socket pieces and whereby the side plates 10 70 are substantially straight throughout their general length. The webs 12 are perforated at preferably two places for the accommodation of binding screw bolts 13 whereby the two side plates may be clamped in proper 75 spaced relation in practice.

At 14 I show one of the brush elements comprising a bundle of bristles 15 and a wrapper 16 at one end serving to bind the bundle of bristles together, said wrapped 80 end being formed in any suitable manner with any suitable filler, such as glue or the like, so as to correspond in shape to the frusto-conical space between the sockets 11 of the two side plates and within which the 85 brush element is securely clamped by means of the binding screws or bolts 13. The brush elements may be made in large quantities and of uniform size and construction so that the operator may easily fill the head 90 consisting of the side plates and connecting parts, and after the brush has served its purpose and the elements have become worn, the worn elements may be discarded and a new set put in their place at a comparatively small cost and very small amount of time.

In addition to the binding screws 13 for securing the brush elements in place, I provide for each of the side plates a stiffening 100 bar 17 extending along the same from one end to the other, said bar spanning the spaces 18 between adjacent sockets and being connected by rivets or the like 19 to each of the sockets, making a strong and rigid construction. The ends 20 of the bars are bent inwardly around the sockets, as shown in Fig. 2 especially, and the opposing ends of the two stiffening bars may be clamped toward each other or together by means of 110 a screw bolt 13 of the same character as those above described. In the process of

manufacture of the improved head, the bars 17 will be secured, as shown, to the side plates and remain permanent parts thereof thereafter.

5 Any suitable form of handle 21 may be employed, and the same may be secured preferably by means of a pair of shells 22, each shell being formed to embrace the center socket member of each side plate and 10 also having side flanges 23 to be engaged by the screws 13 adjacent the center of the device. The shells are secured permanently to the side plates between the bars 17 and said plates during the assemblage of the 15 device at the factory. The handle may be secured in place between the shell members by means of a bolt, rivet or the like, shown at 24.

Having thus described my invention, I 20 claim as new and desire to secure by Letters Patent:—

1. The herein described brush comprising a pair of duplicate side plates, each being formed of a series of frusto-conical sockets 25 and trapezoidal connecting webs, a stiffening bar extending along each of said side plates and secured to the several sockets, the ends of the bar extending around the end sockets, and a series of brush elements ar- 30 ranged between the side plates, and detach-

able clamping means acting through the stiffening bars and side plates securing them in proper position and clamping the brush elements in place, substantially as set forth.

2. The herein described brush construc- 35 tion comprising, in combination, a pair of duplicate side plates formed of sheet metal and comprising a series of curved sockets connected by flat webs, said webs having holes therethrough, a stiffening bar extending along each side plate and secured per- 40 manently to the several socket parts, a pair of handle securing shells secured to the several side plates between the plates and said bars, a series of brush elements of uniform 45 size and shape detachably arranged between the side plates; and detachable means oper- ating through the side plates, the ends of the bars and said shell members, serving to se- 50 cure the parts together with the brush ele- ments between the plates and a handle be- tween the handle members.

In testimony whereof I have signed my name to this specification in the presence of two subscribing witnesses.

HOWARD C. BROWN.
